UNITED STATES PATENT OFFICE.

WILLIAM ROBERT FISHER, OF BARTLESVILLE, OKLAHOMA.

INTERNAL-COMBUSTION-ENGINE STARTER.

1,321,199.

Specification of Letters Patent. Patented Nov. 11, 1919.

Application filed May 5, 1917. Serial No. 166,659.

To all whom it may concern:

Be it known that I, WILLIAM ROBERT FISHER, a citizen of the United States, and a resident of Bartlesville, in the county of 5 Washington and State of Oklahoma, have invented a certain new and useful Improvement in Internal-Combustion-Engine Starters, of which the following is a specification.

10 The present invention relates to starters for internal combustion engines, and more particularly to a starter of the mechanical type.

An object is to provide a mechanical 15 starter embodying spring-motor features adapted to turn over or crank the internal combustion engine, and which may be actuated by releasing an escapement mechanism requiring but slight pressure of the hand 20 or foot. The starter is adapted to be energized or rewound by the internal combustion engine after the latter has been started, the invention providing an improved automatic means for connecting and disconnecting the engine to the spring-winding mechanism.

25 The invention further aims at the provision of a starter embodying these characteristics, and which may be economically constructed from relatively few parts which may be easily assembled, and which occupy but relatively small space, the starter of this invention being adapted to be secured against the side of an internal combustion 35 engine and be connected to the crank shaft thereof.

A still further object of the present invention is to provide a starter construction wherein stock springs may be employed, 40 and which by slight changes in the lengths of several of its parts may accommodate any number of the springs to adapt the starter to internal combustion engines of various sizes.

45 The above, and various other objects and advantages of this invention will be in part described, and in part understood, from the following detailed description of the present preferred embodiment, the same being illustrated in the accompanying drawings 50 wherein:

Figure 1 is an end elevation of a starter constructed according to the present invention, showing the drive chains connected thereto.

55 Fig. 2 is a side elevation of the same, parts

being in section to disclose certain of the interior mechanism.

Fig. 3 is a longitudinal vertical section taken through the same.

60 Fig. 4 is an opposite end elevation of the starter, disclosing the escapement and clutch mechanisms.

Fig. 5 is a transverse section taken substantially on the line 5—5 of Fig. 2, disclosing the rewinding mechanism, the dotted lines showing the same engaged when in position for rewinding the spring.

Fig. 6 is a top edge view of the clutch 65 member employed.

70 Fig. 7 is an outer face view of the escapement wheel taken substantially on the line 7—7 of Fig. 2.

Fig. 8 is a transverse section taken through the rewinding mechanism substantially on the line 8—8 of Fig. 2.

75 Fig. 9 is a detail fragmentary view of the drum ratchet and the pawl for controlling the turning of the same.

80 Referring to these drawings, wherein like parts are designated by similar numerals of reference throughout the several views, the frame of the device comprises a base 10 provided at opposite ends with posts 11 and 12 joined by a longitudinally extending top 85 piece 13. The parts of the frame are preferably made in separate pieces and held together by machine screws or the like to admit of the easy assemblage and disassociation of the parts of the starter.

90 Extending longitudinally through the frame is a drive shaft 14 which projects at its opposite ends beyond the posts 11 and 12 of the frame. One end of the shaft, which may be designated as the forward end thereof, is provided with a drive sprocket 15 over 95 which engages a drive chain 16, the latter being connected in any suitable manner to the internal combustion engine or other device adapted to be driven by the device of this invention. The forward end of the drive shaft 14 is journaled in the upright or post 12, and a secondary or tubular shaft 17, which extends substantially throughout the entire length of the shaft 14, has its rear 100 end journaled in the post 11. The shaft 14 is supported at its rear end in the secondary shaft 17, and is adapted to turn freely in the secondary shaft. A collar 18 is keyed upon the rear end of the drive shaft 14 and is 105 adapted to move longitudinally thereon, and provided at its inner end with a ratchet disk.

110

19 having teeth upon its inner surface which extend in an anti-clockwise direction when the drive shaft 14 is adapted to be turned in a clockwise direction:

5 The rear end of the secondary shaft 17 has fixed thereon an escapement wheel 20 having upon its outer face one or more lugs or projections 21 adapted to register with the teeth of the ratchet disk 19 for interlocking 10 the shafts 14 and 17 when the collar 18 is advanced toward the escapement wheel 20. The escapement wheel is also provided with a pair of outstanding stop pins 22 arranged at diametrically opposed points adjacent to the marginal edge of the wheel 20. Pivotally mounted upon a suitable projection formed on the adjacent post 11, is an escapement lever 23, the upstanding spaced-apart fingers 24 and 25 thereof lying in the 15 path of movement of the pins 22. The escapement lever 23 is pivoted or fulcrumed intermediate the fingers 24 and 25, and it is apparent that upon the reciprocation of the lever 23, the finger 24 is moved out of the 20 path of the pin 22, when the parts are in the position shown in Fig. 4, and the finger 25 is raised into the path of the next succeeding pin 22 when the latter is brought into its 25 new position.

30 The escapement lever 23 is provided with an elongation or projection 26 which extends beyond the finger 25, and which is provided with a laterally extending pin 27 adapted for engagement in a slot 28 formed 35 longitudinally in the lower end of a pull rod 29. The pull rod 29 is slidably mounted in a lug 30 projecting from one side of the frame, and is connected to any suitable operating device by means of which the rod 29 40 may be drawn upwardly to release the mechanism. A clutch lever 31 is formed at its upper end with spaced-apart ears 32 pivotally held by a pin 33 to a lug 34 which projects rearwardly from the frame, and 45 one ear 32 is provided with a forwardly projecting arm 35 bifurcated at its extremity and engaging about the pull rod 29. The arm 35 engages the pull rod 29 at a point spaced downwardly from the lug 30, and a 50 relatively weak spring 36 is mounted on the rod 29 and bears against the arm 35 and holds the lower end of the clutch lever 31 inoperative. A second relatively strong spring 37 is mounted on the pull rod 29 and 55 engages at one end against the under side of the arm 35 and at its opposite end against a pin 38 which is carried upon the pull rod. The spring 37 urges the pull rod 29 downwardly, at which time the upper spring 36 is 60 free to act upon the arm 35 for holding the clutch lever inoperative.

The lower end of the clutch lever 31 is provided with fork arms 39 adapted to engage in an annular groove 40 formed in the 65 periphery of the collar 18. The clutch

lever 31 is adapted to shift the sleeve 18 toward and from the escapement wheel 20, and to interlock the teeth of the clutch disk 19 with the projection 21 of the escapement wheel.

A relatively large drum 41 is rotatably mounted upon the secondary shaft 17, and is adapted to house one or more springs 42 which surround the secondary shaft. In the present instance, a pair of springs 42 is disclosed, the same having their outer ends secured to the drum 41 by rivets 43 or the like, and having their inner ends secured to the secondary shaft 17 by rivets 44 or the like. The drum 41 is free to turn in the frame in 80 one direction, and is held from rotation in an opposite direction by the provision of a ratchet wheel or rim 45 which is preferably secured against the rear end of the drum 41, and which has the teeth thereof extending in 85 an anti-clockwise direction. A spring-pressed pawl 46 is mounted in the lower part of the frame and engages the teeth of the ratchet 45 for holding the latter and the drum 41 from turning in the opposite direction.

The rewinding mechanism is arranged upon the forward end of the device, and comprises a spool or collar 47 fixed upon the drive shaft 14 at the inner side of the post 95 12. The collar 47 is provided, between the flanges thereof, with a centrifugal arm 48 pivotally mounted upon the flanges of the collar and being normally urged inwardly by a spring 49. The free end of the arm 48 100 is headed and provided with a flat outer extremity for engagement at times with the projection of a locking dog 50. The locking dog 50 comprises the lower forked portion of a plate 51 which is pivotally mounted at 105 its closed end upon a pin 52 projecting from the forward end of the drum 41. The upper fork arm 53 of the plate 51 is placed considerably above the locking dog 50 and is provided at its inner side with an inwardly 110 projecting pin 54 lying in the path of a cam 55, the lobe of which is adapted to engage the pin 54 for moving the plate 51 outwardly from the axis of rotation. The cam 55 is carried upon an intermittent gear 56 115 of the star-wheel type provided with relatively deep radiating slots at the points thereof and having concaved dwells between the points. The gear wheel 56, and the cam 55, are mounted for rotation upon a pin 57 projecting from the adjacent end of the drum 41, the pin 57 extending into the slot formed in the plate 51 and receives thereagainst a leaf spring 58 which is secured against the inner edge of the dog 50 120 and adapted to urge the plate 51 downwardly toward the collar 47.

The secondary shaft 17 is provided with a secondary intermittent gear wheel 59, which is provided with a blank or smooth 130

surface throughout practically its entire circumference, and has in one side a concavity or recess 60 adapted to receive the points of the star wheel, one at a time. A pin 61 is carried by the driving gear 59 directly opposite the concavity 60 and is spaced radially beyond the circumference of the driving gear for engagement in the radial slots of the star wheel, one at a time to intermittently 5 rotate the same. The lobe of the cam 55 is arranged in position opposite one of the dwells of the star wheel 56 so that when the latter is at rest in one position, the cam 55 supports the pin 54 and holds the plate 51 in 10 an outwardly extended position.

In operation, when the starter is connected to an internal combustion engine or the like, and it is desired to start the same, it is only necessary to draw upon the pull 20 rod 29, the spring 37 first rocking the clutch lever 31 and moving the sleeve 18 inwardly toward the escapement wheel 20. The slot 28 in the pull rod 29 allows the escapement lever 23 to remain at rest during this initial 25 movement of the pull rod. As the latter is further moved, the spring 37 is compressed under greater tension to overcome the tension of the spring 36, and the lever 23 is rocked to move the finger 24 thereof out of 30 the path of the adjacent pin 22, the finger 25 being raised into the path of the next succeeding pin. The one or more springs 42 employed are now free to turn the secondary shaft 17 with the escapement wheel 20 thereon until the second pin 22 strikes the finger 25. The clutch member 18 interlocks the two shafts so that the main shaft 14 is rotated to carry the gear wheel 15 therewith and thus crank or turn over the internal 40 combustion engine.

As the secondary shaft 17 is turned, the intermittent driving gear 59 is given substantially a half turn, and if the engine fails to start on the first or initial turning of the starter, the operation may be repeated 45 by again drawing on the pull rod 29. This further movement of the secondary shaft 17 carries the driving gear 59 through its complete revolution to engage in the adjacent 50 slot of the star wheel 56 and advance the same one point. In the present instance, the star wheel 56 is disclosed as having six points and radial slots so that it requires twelve consecutive movements of the escapement 55 mechanism and impulses of the starter to rotate the star wheel 56 one complete revolution. When the escapement lever 23 supports one of the pins 22 by the finger 25, the return of the pull rod 29 to its normal position rocks the lever 23 back into normal position to move the finger 25 out of engagement with the pin 22 and to raise the finger 24 into position to engage the said pin 22 to hold it from further turning.

60 When the star wheel 56 is rotated from

the position shown in Fig. 5, the cam 55 is carried therewith and the lobe of the cam releases the pin 54 so that the plate 51 is free for movement inwardly toward the collar 47. The spring 58 yieldingly holds the 70 dog 50 in a position advanced toward the collar 47 and to be engaged by the centrifugal arm 48 when the latter is swung around on the shaft 14 at the required speed to overcome the spring 49. The shaft 14 is driven 75 at this high rate of speed when the engine is started so that the arm 48 interlocks with the dog 50 and draws the plate 51 and the drum 41 around in the direction in which the shaft 14 is turning for rewinding the 80 one or more springs 42. When the springs are rewound, the lobe of the cam 55 strikes the pin 54 and raises the same sufficiently to lift the dog 50 out of engagement with the centrifugal arm 48. This action releases 85 the drum 41 and the latter is held from retrograde movement by the pawl 46 which engages the ratchet teeth 45 carried by the drum. The dotted lines in Fig. 5 disclose the centrifugal arm 48 swung outwardly 90 from the collar 47 and in engagement with the dog 50, the latter drawing the drum 41 in a direction to rewind the spring. The pin 54 engages the shoulder on the cam 55 when the springs 42 are fully unwound to 95 prevent damage to the same.

It is evident that the starter may have a number of impulses equal to the number of points or slots in the star wheel 56 should but one pin 22 be employed. By the provision of the two pins 22 as shown in Fig. 4, the drive shaft 14 is given a half turn at each impulse of the starter and consequently twelve impulses may be had by the provision of a six point star wheel.

105

Various changes and modifications may be made in the details of construction of the above-specifically described starter without departing from the spirit of the invention, and being restricted only by the scope of 110 the following claims.

I claim:—

1. In an internal combustion engine starter, the combination of a driving shaft adapted for connection with an engine, a 115 secondary shaft freely rotatable on the driving shaft, a clutch for interlocking said shafts, a drum rotatably mounted on the secondary shaft, a spring arranged between the drum and said secondary shaft for turning the latter, means for holding the drum from rotation in one direction, escapement mechanism for the secondary shaft, operating means for interlocking the shafts and releasing the secondary shaft to start the 120 engine, a movable member carried by the drum, means between the drum and the secondary shaft for advancing said member toward the first shaft upon the unwinding of the spring, and centrifugally operated 125

130

means carried by the first shaft for interlocking engagement with said lever upon the driving of the first shaft by the engine.

2. In an internal combustion engine 5 starter, the combination of a driving shaft adapted for connection with the engine, a spring motor, a clutch between the spring motor and the driving shaft, releasing means for the spring, an operating rod connected 10 to the releasing means and to the clutch for actuating the same to turn said driving shaft and start the engine, an interlocking member carried upon the spring motor and adapted to be moved toward said driving 15 shaft upon the unwinding of the spring of the motor, and a centrifugal arm carried upon the driving shaft and adapted to move radially therefrom when driven by the engine to interlock with said member and rewind the spring motor.
3. In an internal combustion engine 20 starter, the combination of a driving shaft, a secondary shaft rotatable upon the driving shaft, a drum rotatable on the secondary 25 shaft, a spring carried by the drum engaging the secondary shaft to turn the same, a clutch adapted to interlock said shafts, an escapement mechanism adapted to normally retain the secondary shaft inoperative, 30 a locking dog pivotally mounted on the drum, intermittent gears carried by the drum and the second shaft for moving said locking dog toward and from the first shaft, and a centrifugally operated member carried by the first shaft adapted for interlock-

ing engagement with the dog to connect the drum to the first shaft for rotating the drum.

4. In an internal combustion engine 40 starter, the combination of a driving shaft, a secondary shaft on the driving shaft, a drum freely rotatable on the secondary shaft, a spring arranged between the drum and the secondary shaft for operating the latter, a clutch for interlocking the shafts, an escapement mechanism connected to the 45 secondary shaft for controlling the movement of the same, means for releasing the secondary shaft and interlocking the clutch to rotate said driving shaft, a connection between the driving shaft and internal combustion engine, said driving shaft being adapted to be turned by said engine when started, a locking dog pivotally mounted upon the end of the drum, an intermittent 50 gear mounted on the drum and provided 55 with a cam, a pin projecting from said locking dog for engagement with the cam, a second intermittent gear carried upon the secondary shaft for actuating said first gear, the second gear being adapted to be turned 60 upon the unwinding of the spring to actuate the first gear and the cam and release said locking dog, a spring for said locking dog urging the latter toward the first shaft, and a spring-pressed arm carried 65 upon the first shaft adapted for radial movement upon the driving of the first shaft to interlock the arm with said dog and rotate said drum.

WILLIAM ROBERT FISHER
